CLAIM

The ornamental design for a disc recorder, as shown and described.

DESCRIPTION

FIG. 1 is a first perspective view of a disc recorder showing my new design;

FIG. 2 is a second perspective view thereof wherein the cover portion and the screen portion are in the open position; FIG. 3 is a third perspective view thereof wherein the cover portion is closed and the screen portion is in the open position;

FIG. 4 is a top plan view of FIG. 1 thereof;

FIG. 5 is a front elevational view thereof;

FIG. 6 is a bottom plan view thereof;

FIG. 7 is a right side elevation view thereof, a left side elevational view thereof being a mirror image; and, FIG. 8 is a rear elevational view thereof.

The broken lines showing the inside of the disc recorder of FIG. 2 are for illustrative purposes only and form no part of the claimed design.
